UNITED STATES PATENT OFFICE.

FRANK M. WRIGHT, OF ALBANY, NEW YORK.

DESIGN FOR A JEWELRY-BOX.

59,616.

Specification for Design.

Patented Nov. 8, 1921.

Application filed March 5, 1921. Serial No. 450,100. Term of patent 7 years.

To all whom it may concern:

Be it known that I, FRANK M. WRIGHT, a citizen of the United States of America, residing at Albany, in the county of Albany and State of New York, have invented a new, original, and ornamental Design for Jewelry-Boxes, of which the following is a specification, reference being had to the accompanying drawings, forming a part thereof, in which—

Fig. 2, is a perspective view.

I claim:

The ornamental design for a jewelry box, as shown.

FRANK M. WRIGHT.
